HEDDLE FRAME

Russell P. Drake, Caledonia, Ill., assignor to
Barber-Coleman Company, Rockford, Ill., a
corporation of Illinois

Original application December 15, 1943, Serial
No. 514,313. Divided and this application April
30, 1945, Serial No. 591,008

5 Claims. (Cl. 139—92)

1

The invention pertains to heddle supporting frames and its general aim is to facilitate the removal and replacement of heddles relative to the frame.

More specifically stated, the invention contemplates the provision of a novel and advantageous mounting for the bars upon which the heddles are supported in the frame, permitting easy disassociation of the bars from the frame and presenting no obstruction to the movement of the heddles along the bar.

The objects of the invention thus generally stated, together with other and ancillary advantages, are attained by the construction and arrangement shown by way of illustration in the accompanying drawings forming a part hereof, in which:

Figure 1 is a side elevational view of a heddle supporting frame embodying my invention.

Fig. 2 is a fragmentary elevational view on an enlarged scale illustrating especially the improved means for mounting the heddle supporting bar in the frame.

Fig. 3 is a cross sectional view taken approximately in the plane of line 3—3 of Fig. 2.

This application is a division of my copending application Serial No. 514,313, filed December 15, 1943, now abandoned.

The heddle frame comprises briefly, top and bottom rails 10 and 11, preferably of wood, and end members 12 each comprising a pair of generally U-shaped metal straps 13 and 13' having yoke portions welded together providing parallel end portions 14 spaced apart to receive between them the ends of the rails 10 and 11, such end portions being suitably secured to the rails.

The present invention concerns the mounting of a heddle supporting bar or bars 15 within the frame so as to permit movement of the heddles along the bar without obstruction by the supporting devices. Moreover, the construction is such as to permit of lateral deflection of the ends of the bars whereby the heddles may be removed from the bars, and to permit easy removal of the bars from the frame with or without the heddles. In general, each of the supporting bars is releasably secured at its opposite ends to the end members 12 by means of latch devices 16 forming the subject of my said application, Serial No. 514,313. Intermediate their ends the bars are supported from the adjacent rails 10 and 11 of the frame by means of one or more anchoring devices generally designated 17.

The heddle supporting frame is designed for use with heddles 18 having hooks 19 at opposite

5 ends, and the heddle supporting bars 15 are generally channel shaped in cross section. Thus each provides one leg forming a narrow wall or heddle flange 20 with a free edge portion exposed for engagement by the heddle hooks 19 and the other leg extended to form a relatively wide anchoring member connected to the adjacent side rail by one or more anchoring devices 17, two such devices being herein employed in the case of each rail.

10 In general, the latch devices 16 may comprise a detent member in the nature of a slide bolt 21 mounted for sliding movement transversely of the end member 12 and engageable in an end opening recess formed by the channel of the supporting bar to hold the latter in normal position. As shown, the slide bolt is in the form of a flat plate slidable in the end member 12 of the frame and having its inner end position entered between the legs 20 and 21 of the bar. The plate is mounted on the upper end of a leaf spring 22 anchored to the outer side of the end member 12. The spring is yieldable in the plane of the frame for the purpose of permitting the movement of the slide bolt out of the channel, and the bolt carries a transverse lug 23 for holding the bar in its deflected position, the device having been released and restored to normal position after deflection of the bar. The slide bolt 21 is apertured to receive slidably a bent upper end portion of the spring and the spring is yieldable transversely of the frame to permit disengagement of a U-shaped latch member 24 normally engaging with one edge portion of the end member to hold the bolt against accidental withdrawal from the heddle supporting bar.

15 In the present preferred embodiment of the invention, each anchoring device comprises a rod 22 extending through a hole 23 in the rail and having a connection with the bar disengageable by a short movement of the bar relative to the rod and including in the present embodiment a hook 24. The outer end of the rod is threaded for reception of a nut 25 clamped in position in a recess in the rail by a plate 26, the latter engaging a collar 27 on the nut. By a rotational adjustment of the nut 25 the position of the rod 22 relative to the rail may be adjusted as may be desirable to compensate for any bowing 20 of the rail.

25 The hook 24 of the rod 22 is secured to the supporting bar along the upper edge thereof and therefore in overlying relation to the channel. The upper edge of the bar is formed with transverse flanges 28 carrying lugs 29 shaped to form

loops or open ended sockets for receiving the hooks (Fig. 3). Each hook 34 is preferably formed with a flat side engaging the flange 39 to hold the bar against turning. The lugs 40 are made relatively short so that with the one end of the bar shifted laterally clear of the end member 12, the bar need be moved longitudinally only a short distance to disengage it from the hooks 34.

It will be observed that by the construction provided for supporting the heddle bars in the frame, the heddles may be moved along the bars without interference or obstruction by the anchoring devices 11. Moreover, when desired the heddles may be removed from the bar or new heddles placed thereon simply by releasing the bars at one end from their connection with the frame and swinging such ends laterally into a deflected position at one side of the frame, the bars being held in such deflected positions by the lugs 30 as shown in Fig. 3. The construction also permits removal of the bars from the frame with or without the heddles on the bars, and this by simply releasing the latch devices 16 at one end of the bars and imparting a short endwise movement to the bars after swinging the released ends into deflected positions at the side of the frame, the length of the disengaging movement being determined by the length of the hooks 34 on the anchoring devices.

I claim as my invention:

1. A heddle frame comprising top and bottom rails and end members connecting said rails, heddle supporting means carried by the frame including a bar, an anchoring device carried by one of said rails and having a connection with said bar intermediate the ends thereof, and means connecting the ends of the bars to said end members including a latch device carried by one of the end members and disengageable from one end of the bar to permit lateral deflection of the bar out of the plane of said end member, the connection between said bar and the anchoring device permitting disengagement of the bar from the device by moving the bar a short distance endwise when the said one end thereof is deflected out of the plane of the end member.

2. In a heddle frame having a side rail and an end member perpendicular thereto, a heddle supporting bar having a free end terminating adjacent the inner side of said end member, a latch device carried by the end member and engaging said free end thereof to hold it normally in the plane of the frame, said latch device being movable into an inactive position to permit deflection of the free end of the bar into a position at one side of the frame, and an anchoring device carried by said side rail having a connection with

the bar disengageable by a short movement of the bar longitudinally when said free end occupies its deflected position.

3. In a heddle frame having a side rail and a pair of end members perpendicular thereto, a heddle supporting bar, and an anchoring device for supporting the rod intermediate the ends thereof, said anchoring device comprising a rod projecting from the inner edge of the side rail

10 and having a portion extending longitudinally of the rail in spaced relation thereto, said bar being of channel shape to provide a heddle supporting leg and a bar supporting leg, a flange at the upper edge of the bar supporting leg

15 extending laterally above the channel, and a lug on said flange shaped to form an open ended socket for receiving said end portion of the rod.

4. In a heddle frame having a side rail and a pair of end members perpendicular thereto, a

20 heddle supporting bar, and an anchoring device for supporting the rod intermediate the ends thereof comprising a rod projecting from the inner edge of the side rail and having a portion extending longitudinally of the rail in spaced

25 relation thereto, said bar being of channel shape to provide a heddle supporting leg and a bar supporting leg, a flange at the upper edge of the bar supporting leg extending laterally above the channel, and means on said flange shaped to form

30 an open ended socket for receiving said end portion of the rod, said end portion of the rod having a flat side engaging with said flange to hold the bar against turning.

5. A heddle supporting frame having, in combination, a side rail and a pair of end members perpendicular thereto, a heddle supporting bar having its ends releasably connected to said end members, and a rod carried by the side rail in perpendicular relation thereto and having its

40 inner end portion bent to form a hook extending longitudinally of the rail in spaced relation thereto, said bar having a longitudinal loop formed on one edge and open at one end to receive said hook, and said bar and hook having flat 45 coating surfaces operative to hold the bar against rotation on the axis of said hook.
